CUTLERY HANDLE

Paul C. Culver, Crisfield, Md., assignor to Chas. D. Briddell, Inc., Crisfield, Md., a corporation of Maryland

Application December 7, 1953, Serial No. 27,961

Term of patent 14 years

(Cl. D22—3)

To all whom it may concern:

Be it known that I, Paul C. Culver, a citizen of the United States, residing at Crisfield, in the county of Somerset, and State of Maryland, have invented a new, original, and ornamental Design for a Cutlery Handle, of which the following is a specification, reference being had to the accompanying drawing, forming part thereof:

Fig. 1 is a side elevational view of a cutlery handle showing my new design;

Fig. 2 is a bottom plan view; and

Fig. 3 is an end view thereof looking in the direction of the right end of Fig. 2.

I claim:

The ornamental design for a cutlery handle, as shown.

PAUL C. CULVER.
